(57) **CLAIM**

The ornamental design for a skate guard, as shown and described.

DESCRIPTION

FIG. 1 is a front perspective view of a skate guard showing our new design;

FIG. 2 is a front side elevation view;

FIG. 3 is a rear side elevation view;

FIG. 4 is a right side elevation view;

FIG. 5 is a left side elevation view;

FIG. 6 is a top side plan view; and,

FIG. 7 is a bottom side plan view.

The broken lines in the drawings represent environmental subject matter and form no part of the claimed design.
